UNITED STATES PATENT OFFICE.

JOHN E. SJOMAN, OF OSAGE CITY, KANSAS.

DANGER-SIGNAL FOR RAILWAY-BRIDGES.

1,075,868.

Specification of Letters Patent. Patented Oct. 14, 1913.

Application filed August 9, 1912. Serial No. 714,232.

To all whom it may concern:

Be it known that I, JOHN E. SJOMAN, a citizen of the United States, residing at Osage City, in the county of Osage, State 5 of Kansas, have invented certain new and useful Improvements in Danger-Signals for Railway-Bridges; and I do hereby declare the following to be a full, clear, and exact description of the invention, such as will 10 enable others skilled in the art to which it appertains to make and use the same.

This invention relates to danger signals for railway bridges.

The object of the invention resides in the 15 provision of a danger signal to be placed near the approach of railway bridges and which will act automatically in the event of the bridge being burned or washed away or flooded so as to warn approaching trains of 20 danger and thereby enable such trains to stop in time to avoid serious accident.

With the above and other objects in view, the invention consists in the details of construction and in the arrangement and combination of parts to be hereinafter more 25 fully described and particularly pointed out in the appended claims.

In describing the invention in detail, reference will be had to the accompanying 30 drawings wherein like characters of reference denote corresponding parts in the several views, and in which—

Figure 1 is a plan view of a railway track including a bridge section and having the 35 improved danger signal associated therewith, said signal being in its normal or safety position, Fig. 2, a section on the line 2—2 of Fig. 1, Fig. 3, a side elevation of what is shown in Fig. 1, Fig. 4, a section on the line 40 4—4 of Fig. 1 showing the means for releasing the signal to danger position when the water beneath the bridge is abnormally high said means being in the position it would occupy before effecting the release of 45 the signal, Fig. 5, a view similar to Fig. 4 showing the means for releasing the signal to danger position in the position it would occupy when the signal has been released thereby, Fig. 6, a section on the line 6—6 50 of Fig. 1, Fig. 7, a view similar to Fig. 6 showing the adjacent signal released to danger position, and Fig. 8, a detail perspective view of one of the signals disclosing the holding mechanism.

55 Referring to the drawings there is disclosed a railroad track which includes ter-

60 minal land sections A and B and an intermediate bridge section C. Disposed adjacent the land section A of the track is a signal pole 10 which has pivoted to the upper end thereof a signal arm 11. One end of this arm 11 is provided with a weight 12 which constantly tends to move the arm 11 to danger position as shown in Fig. 7, the movement of the arm 11 under the influence 65 of the weight 12 being limited by means of a stop 13 on the pole 10. Pivotedly connected to the arm 11 between the weight 12 and the pivot of said arm 11 is one end of an arm 14. This arm 14 extends substantially contiguous with the pole 10 and is directed through a guide member 15 carried 70 by the pole 10. Journaled transversely of the pole 10 adjacent the lower end of the arm 14 is a shaft 16 the terminals of which 75 are provided respectively with laterally directed arms 17 and 18. The arm 18 is provided at its free end with a loop 19 for a purpose that will presently appear, while the arm 17 has adjustably mounted thereon 80 a weight 20. Fixed on the shaft 16 between the arms 17 and 18 is a wing or plate 21 which when the shaft 16 is rotated in one direction is adapted to be positioned so as 85 to support the lower end of the arm 14 and thereby hold the signal arm 11 in safety position against the influence of the weight 12. A similar pole and signaling mechanism to that just described is positioned adjacent the track section B and because of the 90 fact that the various parts of the signaling mechanism adjacent the track section B are identical with the parts of the signaling mechanism adjacent the track section A a detail description thereof will be omitted 95 and the same reference characters utilized in indicating the parts as indicate corresponding parts in the signaling mechanism adjacent the track section A.

Mounted upon the bridge section C is a 100 plurality of pulleys 22 over which is trained a cable 23. The terminals of this cable 23 are connected respectively to the loops 19 on the free ends of the arms 18 and is drawn sufficiently taut to move the wings or plates 105 21 carried by each shaft 16 to a position for supporting the arms 14 of respective signals so that the signal arms 11 will be normally held in safety position against the influence of the weights 12. With the signaling mech- 110 anism thus arranged it will be apparent that in case of the bridge section C being burned

or washed out the cable 23 will be severed and the shafts 16 rotated under the influence of the weights 20 so as to release the signal arms 11 for movement to danger position under the influence of the weights 12.

Mounted upon one of the ties of the bridge section C is a pair of spaced plates 24 and 25 and between these plates is pivotally secured one end of an arm 26. The upper end of this arm is beveled and provided with a knife edge 27 while the lower end thereof has secured thereto blocks of buoyant material 28. In the normal position of the arm 26 the major portion of the knife edge 27 thereof is disposed outwardly of the plates 24 and 25 and the cable 23 passes between this knife edge 27 and said plates 24 and 25 so that when the arm 26 is swung in one direction the knife edge 27 will move between the plates 24 and 25 and sever the cable 23 so as to release the signaling mechanisms at each end of the bridge to danger position. The arm 26 is adapted to be moved so as to sever the cable 23 through the influence of water rising beneath the bridge until it engages the buoyant blocks 28. When this engagement takes place the current will act upon the blocks 28 in a manner to effect the desired movement of the arm 26 as will be obvious.

It will of course be understood that the cable 23 may be constructed of various materials as a whole or may be composed of different materials, it being only essential that the portion of the cable which spans the bridge section C be adapted to be severed under the conditions named. That portion of the cable 23 which spans the bridge section C is preferably constructed of hemp rope suitably treated to prevent rotting.

It will be further understood that the signals will be located a sufficient distance from each end of the bridge to enable a train to stop in ample time in the event of danger and that the signals will be provided with light as is customary so that they may be observed at night. The cable may be covered in order to protect same and the number of pulleys increased in proportion to the length of the cable.

What is claimed is:

1. The combination of a bridge, an upright disposed adjacent each end of the

bridge, a signal arm pivoted on each upright, a weight on each arm constantly tending to move same to danger position, a shaft journaled on each upright, lateral arms on each end of said shafts, a weight adjustably mounted on one of said lateral arms of each shaft and constantly tending to rotate said shafts in one direction, a plate fixed on each shaft between the lateral arms, a rod for each signaling arm having one end pivotally connected to each signaling arm and adapted to engage the plate on the adjacent shaft to hold the signaling arm in safe position against the influence of the weight carried thereby, and a cable engaging the bridge and connecting the other lateral arms of said shafts to hold the latter in position to support the signaling arms in safe position, said cable being adapted to be severed under predetermined conditions whereby the shafts are free to rotate under the influence of the weights on respective lateral arms thereof to release the signaling arms for movement to danger position.

2. The combination of a bridge, a semaphore signal disposed at each end of the bridge, means constantly tending to move said signals to danger position, a holding mechanism for each signal adapted to hold the latter in safe position against the influence of said means, a pair of spaced members mounted on the bridge, a plate having one end pivotally mounted between said members and depending from the bridge, the upper end of said plate being beveled and provided with a knife edge normally disposed without said members, buoyant blocks secured to the lower end of the plate and adapted to effect a swinging of the latter under the influence of a current of water beneath the bridge to move the upper end of the plate between said members and a cable passing between the upper end of said plate and said members and connecting the holding mechanisms whereby the movement of said plate under the influence of a current of water beneath the bridge will sever the cable and release the holding mechanisms.

In testimony whereof, I affix my signature, in presence of two witnesses.

JOHN E. SJOMAN.
